QUICK-OPENING ENVELOPE

Eugene B. Berkowitz, Kansas City, Mo., assignor
to Berkowitz Envelope Company, Kansas City,
Mo., a corporation of Delaware

Application May 17, 1941, Serial No. 393,968

5 Claims. (CL. 229—80)

This invention relates to envelopes particularly for containing individual quantities of materials, for example an individual portion of powdered chocolate as used at soda fountains, restaurants, and the like, in the preparation of a cup of chocolate beverage.

The present application is directed to an improvement in the envelope structure disclosed in my copending application Serial No. 251,001, filed January 14, 1939.

In envelopes of the type illustrated in the above entitled application, it is found that the spots of adhesive penetrate the fibers of the paper and the fibers are so firmly adhered that when the sealing flap is pulled loose the fibers do not break apart cleanly and tend, in some instances, to tear the sealing flap.

It is, therefore, a principal object of the present invention to provide sealing spots of a shape and form that the edges of the non-adherent material which limits the effective sealing area form shear points on which the fibers are severed when the sealing flap is pulled to open position.

In accomplishing this and other objects of the invention, as hereinafter pointed out, I have provided improved structure, the preferred form of which is illustrated in the accompanying drawing, wherein:

Fig. 1 is a perspective view of an envelope constructed in accordance with the present invention and showing the sealing flap in sealed position.

Fig. 2 is a perspective view of the inner side of a blank from which the envelope is formed, portions of the side flaps being turned back to illustrate the adhesive repellent coating.

Fig. 3 is a perspective view of the blank with the side flaps folded and sealed to each other, but showing the end flaps in extended position.

Fig. 4 is a perspective view of the envelope illustrated in Fig. 1, but showing the method of breaking the seal of one of the end flaps to permit emptying of the contents of the envelope.

Fig. 5 is a perspective view of the envelope showing manipulation thereof in shaping a spout of the pull tab so as to facilitate emptying of the contents into a container.

Referring more in detail to the drawing:

I designates an envelope blank shaped to provide a substantially rectangular body portion 2 defined by lines of fold 3—4 and 5—6. Extending laterally from the lines of fold 3 and 4 are side flaps 7 and 8, the side flap 8 being of greater width than the flap 7 so that when they are folded over the body portion 2 the marginal edge

9 thereof will overlap a stripe of sealing gum 10 on the marginal edge of the flap 7 to form a seam 11 offset from the median line of the envelope, as shown in Fig. 3.

5 The ends of the body portion 2 are provided with end flaps 12 and 13. The flap 12 is of conventional shape, but the flap 13 has a central, tab-like portion 14 projecting therefrom and which is provided with a substantially straight 10 lower edge 15 extending parallel with the fold line 5. The tab 14 may have diverging side edges 16 and 17 merging into the edges of the end flap on curves as indicated at 18 and 19. The flap 12 may be provided with gum 20 extending across the width thereof to seal against the side flaps 7 and 8 when the flap is folded on the line of fold 6. The end flap carrying the tab-like portion 14 has a series of gum spots 21 applied on the inner face thereof and which 15 are adapted to seal against limited sealing areas 22 on the side flaps 7 and 8 when the flap is folded on the line 5. The limited sealing areas 22 are preferably of circular shape and defined within the field of a coating material 23 applied over the area of the side flaps covered by the sealing flap.

20 The coating material 23 may consist of ink having an oil base so that it is repellent to the adhesive spots 21 when the adhesive dries, but provides a sufficient amount of cohesion with the adhesive when the gum is moist to retain the flap in folded position. The circular edges 24 25 of the coating which define the sealing areas 22 form shear points on which adhering fibers are caused to tear off when the flap is opened, as later described.

25 The blank forming the envelope may be printed with the adhesive repellent coating material 23 and then folded in a conventional envelope forming machine and wherein the gum 20 is applied to the flap 12, then dried, and the blank delivered to a folding mechanism which folds the side flaps 7 and 8 on the side folds 3 and 4 after the seal gum 10 has been applied so that 30 the side flaps are connected from the back portion of the completed envelope as shown in Fig. 3. After the blank has been thus folded, the inked portions of the side flaps appear as in Fig. 3 and conform to substantially the shape of the end flap 14. In the next operation, the flap 14 35 is provided with the gum or adhesive spots 21 and folded over the coated area of the side flaps on the fold line 5 to bring the gum spots in sealing contact with the areas 22. Attention is directed to the fact that the adhesive spots are of

40 45 50 55

sufficient area to provide a sufficient amount of adhesion with the coating 23 to retain the flap folded during the remaining operations on the envelope and until a positive seal is effected with the limited areas 22.

Upon drying of the adhesive, those portions in contact with the coating 23 crystallize and have no function after the tackiness thereof has been destroyed incidental to drying of the adhesive. Therefore, after the adhesive has dried, the closure of the end flap 14 is dependent entirely upon the portions of the adhesive adhering to the circular areas 22 wherein the seal is directly between the fiber surface of the flap 14 and that of the side flaps of the envelope.

The envelope may then be filled through the opposite end in a conventional filling machine, after which the gum 20 is moistened and the flap 12 folded on the line 1 so that the gum sealingly engages the side flaps to retain the contents.

When the envelope is opened, the tab 14 may be grasped between the thumb and forefinger as shown in Fig. 4, and drawn retractive to break the seal at the spots 22. As above pointed out, the adhesive penetrates the fibers of the paper when it is moist, and when dry firmly engages the fibers of the paper, so that when the flap is pulled open, as shown in Fig. 4, the adhered fibers on the flap remain in sealing engagement with the fibers of the sealing spots, but as the fibers are drawn along the curved edges 24 they are severed and break loose so that they do not cause tearing of the flap.

Attention is particularly directed to the fact that the curved shear edges defined by the coating are arranged transversely to the direction of the pull of the flap when it is opened so that each fiber is drawn against a portion of the curved shear edge and therefore each fiber is severed cleanly and individually. The fibers nearest the ends of the diameter of the sealing areas are first severed, followed by severance of the intermediate fibers as the flap is pulled open, until the fibers at the longitudinal diameter are severed. With this arrangement, the fibers are more easily severed and the flap is readily opened.

What I claim and desire to secure by Letters Patent is:

1. A quick opening envelope formed of fibrous material including, a body portion and a seal flap portion extending along an opening in said body portion through which contents of the envelope is adapted to be emptied, a gum repellent coating on one of said portions and contacting the other portion when the seal flap portion is in sealed position, said portion provided with the gum repellent coating having restricted uncoated sealing spaces within said coated area, gum between said portions for effecting seals at said restricted spaces, and substantially arcuate cutting edges provided by said coating on sides of the sealing spaces nearest said opening for severing any fibers which are imbedded in said gum when the flap portion is pulled loose in opening of the envelope.

2. A quick opening envelope formed of fibrous material including, a body portion and a seal flap portion extending along an opening in said body portion through which contents of the envelope is adapted to be emptied, a gum repellent coating on one of said portions and covered by the other when the flap portion is folded over the body portion, said gum repellent coating having

restricted sealing spaces within the area thereof with the edges of said gum repellent coating at said spaces forming arcuate cutting edges, and gum between said portions, said gum repellent coating having a character to effect adhesiveness of the moist gum thereto and to repel adhesiveness of the gum when the gum is dry whereby the gum is effective over the coated area including said restricted sealing spaces when the gum is moist and effective only at the sealing spaces when the gum is dried with the cutting edges serving to shear any fibers imbedded in said spaces when the flap portion is pulled loose at the sealing spaces upon opening of the envelope.

3. A quick opening envelope formed of fibrous material including, a body portion and a seal flap portion extending along an opening in said body portion through which contents of the envelope is adapted to be emptied, a gum repellent coating on one of said portions and engaged by the other when the seal flap portion is closed over the body portion, said portion provided with a coating having circular uncoated sealing spaces within the gum repellent coating, cutting edges formed by the coating at edges of the circular sealing spaces nearest said opening, and gum between said portions for effecting seal of the portions at said spaces, said cutting edges being adapted to sever fibers that are imbedded in the gum of said spaces when the fibers are drawn thereacross upon pulling of the seal flap portion loose at said sealing spaces.

4. A quick opening envelope formed of fibrous material including, a body portion and a seal flap portion extending along an opening in said body portion through which contents of the envelope is adapted to be emptied, a gum repellent coating on one of said portions and covered by the other when the flap portion is folded over the body portion, said gum repellent coating having restricted circular sealing spaces within the area thereof with the edges of said gum repellent coating at said spaces forming arcuate cutting edges, and gum between said portions, said gum repellent coating having a character to effect adhesiveness of the moist gum thereto and to repel adhesiveness of the gum when the gum is dry whereby the gum is effective over the coated area including said restricted circular sealing spaces when the gum is moist and effective only at the sealing spaces when the gum is dried with the cutting edges serving to shear any fibers imbedded in said spaces when the flap portion is pulled loose at the sealing spaces upon opening of the envelope.

5. A quick opening envelope formed of fibrous material including, a body portion and a seal flap portion extending along an opening in said body portion through which contents of the envelope is adapted to be emptied, a gum repellent coating on one of said portions and contacting the other portion, gum between said portions and crystallized upon the gum repellent coating, said portion provided with the gum repellent coating having restricted uncoated sealing spaces within said coated area of a shape forming cutting edges of said crystallized gum converging from opposite sides of said areas to a common meeting point in the direction of the opening for severing any fibers which are embedded in the gum of said sealing areas when the flap portion is pulled loose in opening the envelope.

EUGENE B. BERKOWITZ.
